UNITED STATES PATENT OFFICE.

EDWARD P. LE COMPTÉ AND RUBIN COLVIN, OF PARK CITY, UTAH.

CRUTCH.

1,157,314.

Specification of Letters Patent.

Patented Oct. 19, 1915.

Application filed April 4, 1914. Serial No. 829,531.

To all whom it may concern:

Be it known that we, EDWARD P. LE COMPTÉ and RUBIN COLVIN, citizens of the United States, residing at Park City, in the county of Summit and State of Utah, have invented certain new and useful Improvements in Crutches, of which the following is a specification.

Our invention relates to improvements in crutches, and has particular reference to a crutch formed of a preferably metallic tube or pipe, split longitudinally to provide spaced arms, which carry the arm rest.

An important object of the invention is to provide reliable and simple means whereby the crutch may be longitudinally adjusted in a quick and convenient manner.

A further object of the invention is to provide means whereby the hand grip may be quickly and conveniently vertically adjusted.

A further object of the invention is to provide means whereby the arm rest may be readily separated from the arms of the standard or body portion of the crutch.

A further object of the invention is to provide means whereby the hand grip and the foot rod of the crutch may be simultaneously vertically adjusted.

30 A further object of the invention is to provide means of the above-mentioned character, which are simple in construction, inexpensive to manufacture, strong, and durable.

35 Other objects and advantages of this invention will be apparent during the course of the following description.

In the accompanying drawings forming a part of this specification and in which like numerals are employed to designate like parts throughout the same:—Figure 1 is a side elevation of a crutch embodying our invention; Fig. 2 is a plan view of the same; Fig. 3 is a horizontal section taken on line 45 3—3 of Fig. 1; Fig. 4 is a side view of a crutch embodying a modified form of my invention. Fig. 5 is a detail longitudinal section through a portion thereof, showing the means to lock the hand grip in place; Fig. 6 is a side elevation of a crutch embodying a still different form of our invention; and Fig. 7 is a detail section through the lower end of the same.

In the drawings wherein is illustrated 50 preferred embodiments of our invention, each crutch is shown as formed of a prefer-

ably metal tube or pipe, split longitudinally for the greater portion of its length, providing upper spaced arms 10, carrying at their lower ends a foot-tube 11, as shown. The arms 10 are curved or semi-cylindrical in cross-section, whereby they possess the desired degree of stiffness.

In each crutch, the upper ends of the arms 10, are (see Fig. 2) provided with headed bolts 12, to operate within key-hole openings 13, formed through the opposite ends of an arm-rest 14, as shown. These key-hole openings 13 have their large ends arranged innermost, and are provided with 60 enlarged upper grooves 14, in registration with the inner large portions of the openings 13, as shown. It is thus seen that the arm-rest 14 may be secured to the arms 10 by bending the upper ends thereof inwardly, 65 so that the headed bolts 12 may pass through the large inner ends of the key-hole openings 13, the arms being released whereby the headed bolts will pass into the outer small 70 portions of the openings 13, with their heads 75 in the grooves 14, flush with the outer surface of the arm-rest 14.

In the forms of the invention shown in Figs. 1 and 6, the numeral 15 designates a hand grip, provided at its ends with right and left screw-threaded extensions 16, adapted to engage in a selected one of the pairs of screw-threaded openings 17, which are arranged in spaced superposed relation, as shown. From the foregoing, it is obvious, 80 that after the arm rest 14 has been removed from the arms 10, the hand grip 15 (in Figs. 1 and 6) may be readily removed to be vertically adjusted, by first turning the same in the proper direction.

In Fig. 1, the foot-tube 11 has its bore internally screw-threaded, to receive a screw-threaded foot-rod 18, provided at its lower end with a shock absorbing foot 19, preferably formed of rubber, as shown. It is obvious that the crutch in Fig. 1 is longitudinally adjusted by turning the foot-rod 18.

In Fig. 6, the foot-tube 11 has a smooth bore receiving a smooth foot-rod 20, which is longitudinally adjustable therein, and provided at its lower end with a foot 21, preferably formed of rubber. To clamp the foot-rod 20 in adjustment in the foot-tube 11, in Fig. 11, such foot-tube is provided with a longitudinal groove 22, adjacent 100 which are ears 23, having screw-threaded 105 apertures 24. A thumb bolt 24 passes

through these apertured ears, to contract or expand the tube 11, to clamp or release the foot-rod 20, as the case may be.

In Figs. 4 and 5 the numeral 25 designates a longitudinally adjustable rod, the lower end of which serves as a foot-rod, and is longitudinally movably mounted in the foot-tube 11, (in Fig. 4) having a smooth bore. To the lower end of the rod 25 is secured a foot 26, preferably formed of rubber. The upper end of the rod 25 extends upwardly a sufficient distance to be connected with a hand grip 26', for movement therewith as shown. This hand grip is provided at its ends with screw-threaded reduced extensions 27, adjustably mounted in longitudinal slots 28. The extensions 27 carry thumb-nuts 28, whereby the hand-grip may be clamped to the arms in a desired vertical position, with the foot-rod in a corresponding position.

In view of the foregoing it is thought that no further explanation of the invention is necessary.

It is to be understood that the forms of our invention are to be taken as preferred examples of the same, and that various changes in the shape, size, and arrangement of parts may be resorted to, without departing from the spirit of the invention and the scope of the subjoined claims.

Copies of this patent may be obtained for five cents each, by addressing the "Commissioner of Patents, Washington, D. C."

Having described the invention what we claim is:—

1. A crutch of the character described, comprising a body portion including a pair of spaced arms provided at their upper ends with headed studs, and an arm-rest provided near its ends with key-hole openings to receive the headed studs. 35

2. A crutch of the character described, comprising a longitudinally split metallic tube forming a lower tubular portion and upwardly extending spaced hollow arms having their concave surfaces arranged innermost, a foot element extending into the lower tubular portion, an arm rest arranged adjacent the upper ends of the spaced arms, means detachably connecting said arms and arm rest and adapted to disconnect them upon the inward movement of said arms toward each other, and a hand grip arranged beneath the arm rest with its ends extending into the concave surfaces of said arms to be held thereby against lateral displacement with relation thereto. 40 50 55

In testimony whereof we affix our signatures in presence of two witnesses.

EDWARD P. LE COMPTE.
RUBIN COLVIN.
